(57) **CLAIM**

The ornamental design for a linkable fluorescent lamp with aluminum reflector and crystal lamp cover, as shown and described.

DESCRIPTION

FIG. 1 shows a perspective view of my claimed design.
FIG. 2 shows an exploded perspective view of my claimed design.

FIG. 3 shows a front view of my claimed design.

FIG. 4 shows a rear view of my claimed design.

FIG. 5 shows a top view of my claimed design.

FIG. 6 shows a bottom view of my claimed design.

FIG. 7 shows a left side view of my claimed design; and,

FIG. 8 shows a right side view of my claimed design.

The fluorescent lamp is broken away to indicate indefinite length.
